UNITED STATES PATENT OFFICE.

GUSTAV HILGENSTOCK, OF DAHLHAUSEN-RUHR, GERMANY.

TREATMENT OF GASES GIVEN OFF IN THE DESTRUCTIVE DISTILLATION OF COAL, &c.

994,315.

Specification of Letters Patent. Patented June 6, 1911.

No Drawing.

Application filed September 19, 1910. Serial No. 582,662.

To all whom it may concern:

Be it known that I, GUSTAV HILGENSTOCK, a subject of the Emperor of Germany, residing in Dahlhausen-Ruhr, Westphalia, 5 Prussia, Empire of Germany, have invented a certain new and useful Improvement in the Treatment of Gases Given Off in the Destructive Distillation of Coal, Lignite, Peat, and the Like, of which the following 10 is a true and exact description.

The present invention is an improved method of treating the hot gases resulting from the destructive distillation of coal, lignite, peat, and the like, and the object of 15 the present invention is to provide a simple and satisfactory method for separating tar from the hot gases, and recovering or removing some of the constituents of such gases.

20 Heretofore it has been proposed, in the German Patent No. 203,254, to wash the tar out of the hot gases by spraying tar into the gases, and to recover the ammonia by passing the gases through an acid bath. With

25 such a treatment, however, I have found that a portion of the fixed ammonia, chiefly ammonium chlorid, is taken up by the washing tar. This can not be washed out of the tar by mixing gas liquor with the latter

30 to thereby permit the recovery of the ammonia by subsequently passing the gas liquor through the acid bath. I have discovered, however, that by washing the gases a second time, after they pass through the

35 acid bath, with the wash tar of the first washing operation, as by spraying the wash tar into the gases, the ammonia in the wash tar is washed out by the water vapors condensing from the gases, and may thereby

40 be recovered. This washing of the ammonia out of the tar may be facilitated by the admixture of gas liquors with the tar, and also by evaporating gas liquor and mixing the resultant vapors with the gases after the

45 gases have passed through the acid bath.

A second advantageous result had by reason of the second washing is the dissolving of the naphthalene out of the gases by the tar. The naphthalene thus removed from the gases has heretofore often become annoying when the tar has been eliminated at a high temperature.

50 The second washing of the gases, as described, may, by a suitable regulation of the relative quantities of gases and tar and of

the temperature conditions, be caused to result in the absorption from the gases of the vaporous illuminants contained therein, such as benzol and toluol vapors and the like, and their ultimate recovery if it is not 60 desired to use the gases for illuminating purposes. If it is desired to use the gas for illuminating purposes, the conditions may be so regulated, however, that the second washing will not remove the illuminants 65 from the gases.

When it is desired to remove the illuminants, the wash tar for the second washing should be as cool as is practically possible, with the cooling medium (cooling water) 70 available. To augment the absorption of the illuminants, tar oils may also be added to the washing tar. By this procedure the bulk, if not all, of the illuminants may be extracted from the gases. By subsequently 75 heating the washing tar to the temperature required for the first washing operation, which may be up to seventy or eighty degrees centigrade, a considerable portion of the absorbed hydro-carbons may be evaporated, especially if the reheating of the tar 80 is done in a current of gas or steam. The evaporated hydro-carbons may be recovered and utilized in various ways well known to 85 those skilled in the art.

Where it is not desired to impair the illuminating value of the gas by the second washing this may be avoided by increasing the temperature of the washing tar, and decreasing its relative volume as compared 90 with the conditions employed when it is desired to have the illuminants absorbed.

Having now described my invention, what I claim as new and desire to secure by Letters Patent, is:

1. The method of treating the hot gas resulting from the destructive distillation of coal, lignite, peat and the like, which consists in washing the gas with tar, then passing the gas through an acid bath, and then washing the gas a second time with the washing tar of the first washing operation. 100

2. The method of treating the hot gas resulting from the destructive distillation of coal, lignite, peat, and the like, which consists in washing the gas with tar, then passing the gas through an acid bath, and then washing the gas a second time with the washing tar of the first washing operation 105 mixed with gas liquor. 110

3. The method of treating the hot gases resulting from the destructive distillation of coal, lignite, peat, and the like, which consists in washing the gas with tar, then passing the gas through an acid bath, and then admixing with the gas the vapors or steam evaporated from gas liquor, and then wash-

ing the gas a second time with the washing tar of the first operation.

GUSTAV HILGENSTOCK.
